ATTY.

UNITED STATES PATENT OFFICE.

ERNEST E. SANDERS, OF RENO, NEVADA.

MAGNET.

Application filed October 3, 1927. Serial No. 223,731.

My invention relates to improvements in magnets, of either electro or permanent type, wherein a detachable pole, consisting of a suitably shaped probe, operates in conjunction with an adjustably mounted opposite pole to vary the strength of a magnetic field between said poles whereby foreign magnetic particles, such as steel chips and the like, may be removed from an eye-ball.

10 The primary object of the present invention is to provide a new and improved magnet for removing magnetic particles from an eye-ball.

Another object of the invention is to provide a new and improved magnet of the type described having a detachable pole consisting of a suitably shaped probe, whereby said probe may be detached and another shape of probe substituted therefor.

20 A further object of the invention is to provide a U-shaped magnet having one of its poles adjustable relatively to the other pole whereby the strength of the magnetic field between said poles may be varied, or 25 adjusted and controlled.

I accomplish these and other objects by means of the preferred form of the device disclosed in the drawings forming a part of the present application wherein like characters of reference are used to designate similar parts throughout the specification and drawings, and in which—

Fig. 1 is an elevation, partly broken, disclosing my improved magnet; and

35 Fig. 2 is an end elevation thereof.

Referring to the drawings the numeral 1 is used to designate in general a U-shaped magnet having north and south poles 2 and 3 respectively, the south pole 3 being provided with a detachable probe 4 of suitable shape whereby said probe may be removed and other probes of various shapes and sizes, according to the nature and purposes for which they are to be used, may be substituted therefor.

The end of the north pole 2 is hingedly or otherwise movably mounted whereby it may be moved toward and away from the opposite pole or probe 4 to vary the strength

of the magnetic field between said poles 50 whereby said field may be adjusted and controlled. In the preferred form of the invention the north pole may be hingedly connected as at 6 so that the said north pole 2 may be moved toward and away from the 55 south pole.

In operation, when it is desired to remove a magnetic foreign particle from an eye-ball, a suitable probe, depending upon the nature and location of the foreign magnetic particle, is attached to the south pole which is then placed as close as possible to the foreign particle to be removed.

By manipulating the movable pole the operator is able to not only control the direction and path of the lines of magnetic force, but to also direct the greatest amount of magnetic flux in a direction which will dislocate and remove the foreign magnetic particle, such as a piece of steel, from an eye-ball. In this manner the foreign particle may be placed within the strongest magnetic field and being magnetized by mutual magnetic induction will add to its mutual magnetic attraction and thereby assist in removing itself.

It is thus obvious that the path of the magnetic flux may be directed by means of the movable pole so as to exert the greatest possible influence upon the foreign magnetic particle of which the magnet is capable, thereby bringing the said foreign particle directly within the path of the greatest magnetic flux, mutually magnetizing said particle, and thereby assist in its removal.

Having thus described my invention what I claim as new and desire to secure by Letters Patent is—

1. A U-shaped magnet for removing particles from the eye-ball having one of the poles thereof hingedly mounted thereon and adjustable relatively to the other pole whereby the strength of the magnetic field of said magnet may be controlled.

2. A U-shaped magnet for removing particles from the eye-ball comprising a pair of poles, one of which consists of a detachable probe and the other having its end

pivotsly connected to adjust and control a magnetic field between said poles.

3. A U-shaped magnet comprising a pair of parallel poles, one of which consists of a detachable probe for removing steel and other foreign magnetic particles from an eye-ball, and the other pole consisting of a hingedly connected member arranged to

move toward and away from said probe to adjust and control a magnetic field between said poles whereby the strength of said field may be varied.

In witness whereof, I hereunto set my signature.

ERNEST E. SANDERS.
